UNITED STATES PATENT OFFICE

164,929

COMBINED BOTTLE AND STOPPER

William W. Hobé, New York, N. Y.

Application June 18, 1951, Serial No. 15,595

Term of patent 3½ years

(Cl. D58—8)

To all whom it may concern:

Be it known that I, William W. Hobé, a citizen of the United States of America, residing in New York city, county of New York, and State of New York, have invented a new, original, and ornamental Design for a Combined Bottle and Stopper, of which the following is a specification, reference being had to the accompanying drawing, forming part thereof, wherein,

The rear of the perfume bottle is identical in appearance to the front shown.

I claim:

The ornamental design for a combined bottle and stopper, substantially as shown and described.

WILLIAM W. HOBÉ.
